APPARATUS FOR FORMING CORNERS

Leo J. Trahan, Cohoes, N. Y.

Application October 25, 1949, Serial No. 123,380

15 Claims. (Cl. 223—2)

1

This invention relates to apparatus for forming corners on multiple thickness cloth garments such as coat lapels, belts, shirt collars, and the like.

In the manufacture of cloth garments having pointed or rounded ends or corners, it is customary to stitch together two or more pieces or plies of fabrics having the general configuration desired with the wrong sides out. Excess material is then trimmed from the sides adjacent the corner to prevent a bulky corner in the finished garment. After the trimming operation, the garment is turned so that the right sides are out and the stitched edges inside. The corner is then formed to the final shape desired and the garment pressed. These operations have formerly been manually performed in separate steps, however, it is desirable to provide compact and simple apparatus under the control of a single operator for performing all of the operations necessary to form a finished garment corner.

An object of this invention is to provide improved apparatus for performing trimming, turning, and shaping operations on a multiple thickness cloth garment to form a corner thereon.

Another object of this invention is to provide improved apparatus for forming a garment corner.

A further object of this invention is to provide improved compact and simple apparatus under the control of a single operator for performing all of the operations necessary to form a garment corner.

A still further object of this invention is to provide improved apparatus for trimming, turning, forming, and pressing a garment corner.

Yet another object of this invention is to provide improved apparatus for trimming, turning, forming, and pressing opposed corners of a garment successively.

Still another object of this invention is to provide improved apparatus for performing trimming, turning, forming, and pressing operations on a multiple thickness cloth garment to form a corner thereon wherein steam-forming liquid is injected onto the corner or pressing means during the pressing operation to improve the press and finish of the garment.

Further objects and advantages of this invention will become apparent and the invention will be better understood from the following description referring to the accompanying drawings, and the features of novelty which characterize this invention will be pointed out with particularity in the claims annexed to and forming part of this specification.

2

In the drawing, Fig. 1 is a front elevational view of an embodiment of this invention; Fig. 2 is a fragmentary side elevational view, partly in section, illustrating the apparatus of Fig. 1; Fig. 3 is a fragmentary top view of the apparatus of Fig. 1; Fig. 4 is a fragmentary side view showing the trimming action of the apparatus of this invention; Fig. 5 is a fragmentary front view further illustrating the trimming action; Fig. 6 shows the untrimmed garment corner with the wrong side out; Fig. 7 shows the garment after trimming; Fig. 8 shows the manner in which the trimmed garment corner is turned and formed; and Fig. 9 shows a cross-sectional view of the steam-forming liquid injection mechanism of Fig. 1.

Referring now to Figs. 1, 2, and 3, which illustrate an embodiment of this invention adapted to form a pointed corner such as the end of a shirt collar, there is shown a stationary supporting frame member 1 having a base portion 2 adapted for table mounting. The frame 1 is provided with an opening 3 formed therein and two leg portions 4 extending from either side of the opening. A garment receiving and guiding member comprising a flat prong portion 5 and a mounting portion 6 is pivotally mounted between the leg portions 4 as at 7. The garment receiving member 5 is adapted to be manually pivoted from a first vertical position, as shown in Fig. 2, through the opening 3 to a second position as will be hereinafter described. The prong portion 5 is adapted in its first position to have a garment 8 placed thereover, the garment comprising two or more roughly cut plies of fabric with the wrong side out stitched together as at 9 in Fig. 6.

In order to form a finished pointed corner on the garment 8, it is necessary to trim excess material adjacent the point to prevent bulkiness when the garment is turned right side out. To perform this operation, two stationary cutting blades 10 are secured to the side of the frame 1 remote from the first position of the receiving member by adjusting screws 11, slots 12 in the blades permitting adjustment of the blades to secure the proper trimming action. The adjusting screws 11 also permit removal of the blades 10 for sharpening. The blades 10 are positioned adjacent the opening 3 and adjusted by screws 11 to provide the desired trimming of excess material adjacent the garment corner. A shearing member 13 formed of hardened steel is pivotally mounted in the opening 3 by pivots 14 and is formed with a V-shaped end ground to two cutting edges which cooperate with the cutting blades

10 to provide the trimming action on the garment 8, the prong 5 of the receiving member serving only to guide the garment during the trimming operation. The shearing member 13 is provided with an operating lever portion 15 which is operatively engaged by lever 16 which is also pivoted in opening 3 as at 17. The lever 16 is actuated by a pitman rod 18 which is connected to foot treadle 19 by a piano wire link 20. The pitman rod 18 extends through the base portion 2 and is provided with a stop 21 to limit upward movement of the rod. A compression spring 22 surrounds pitman rod 18 and serves to return the rod to the position shown in Fig. 2 while spring 23 connected between lever 16 and the shearing member 13 resiliently biases the shearing member to the position shown in Fig. 2. Adjustable stop 24 limits the travel of lever 16 and thus of shearing member 13.

To perform the trimming operation, the garment receiving member with the untrimmed garment 8 of Fig. 6 positioned on the prong 5, is manually pivoted through the opening 3, as shown in Fig. 4, until the corner 25 is in contact with the shearing member 13. The treadle 19 is then depressed to the position shown at 26 causing lever 16 to engage lever portion 15 of shearing member 13 to move the shearing member, with the point 25 of the garment 8 held thereon by manual pressure on the receiving member, toward and through the opening 3, as shown in Fig. 4, the cutting edges of the shearing member 13 cooperating with the cutting blades 10 to shear or trim the excess material from the point 25, as shown in Fig. 5, to produce the trimmed edges 27 as shown in Fig. 7. The garment receiving member is resiliently biased into its first vertical position by a coil spring 28 and adjustable stop 29 serves to limit the outward movement of the garment receiving member away from the cutting blades 10 and opening 3 after the trimming operation.

After the trimming operation, the garment must be turned so that the right side is out and the corner must be formed to the final shape desired and pressed. To perform these operations, a forming member 30 is provided having the correct shape to form the garment corner to the final shape desired. The forming member 30 is mounted on a hub portion 31 carried by a supporting arm 32 which is pivotally mounted on the frame 1 as at 33. The arm 32 is formed with an operating portion 34 which is operatively engaged by lever 35, which in turn is connected to lever 36 at pivot 37 as will be hereinafter described. A coil spring 38 serves to normally bias the arm 32 and forming member 30 into the position shown at 39 in Fig. 3 so that the forming member is adjacent the prong member 5 in its first position as shown in Fig. 8. When the forming member 30 and prong member 5 are in these relative positions, the garment 8 can be transferred to the forming member 30 and reversed during the transfer so that the right side is out and the stitches 9 are inside as shown in Fig. 8.

After the garment 8 has been transferred to the forming member 30 from the prong 5 after the trimming operation, it is desirable to press the pointed corner on the forming member 30. To accomplish this objective, the arrangement now to be described is provided. A pair of heated pressing pads 40 and 41 are movably mounted on the frame 1 in a normally spaced apart relationship as shown in Fig. 1. Pitman

5 rod 42 is connected to lever 36 and is in turn connected to treadle 43 by a piano wire link. A stop 44 is provided to limit upward movement of the rod 42 and compression spring 45 serves to return the rod 42 to the normal position. The apparatus described immediately above swings 10 the supporting arm 32 and forming member 30 from the position 39 directly over the prong 5, by 90° so that the forming member 30 with the 15 trimmed and turned garment thereon is between the heated pressing pads 40 and 41, as shown in solid lines in Fig. 3. When the forming member 30 is in its first or garment receiving position above the prong 5, the lever 36 is in the position 20 shown by the dashed lines at 46 and the treadle 43 is in the position shown in dashed lines at 47. Depression of the treadle 43 to the position 25 shown in solid lines in Fig. 2 causes pitman rod 42 to move the lever 36 to the position shown in solid lines in Fig. 1 in turn causing lever 35 to 30 operatively engage operating portion 34 of supporting arm 32 to move forming member 30 between the heated pressing pads 40 and 41. Adjustable stop 49 limits movement of operating portion 34, supporting arm 32, and forming portion 30 between the heated pressing pads 40 and 41 and adjustable stop 49 limits movement of these elements in the position 39. Coil spring 51 retains the lever relationship of levers 36 and 35 35 during operation of operating portion 34 and supporting arm 32, however, permits continued downward movement of lever 36, as will be hereinafter described, after operating portion 34 has reached stop 49.

35 Heated pressing pad 40 is movably supported by a pair of rods 52 which are slidably supported by brackets 53 on either side of frame 1. Springs 54 on the rods 52 serve to bias the heated pressing pad 40 toward the open position 40 as shown in Figs. 1 and 3 and to compensate for varying thicknesses of cloth during the pressing operation. The pad 40 is moved into the pressing position by a pair of levers 55 which engage the ends of the rods 52. The levers 55, 45 on either side of the frame 1, are pivoted as at 56, and are actuated by an engaging portion 57 of lever 36 responsive to movement of treadle 43 to the position shown in dashed lines at 48. Heated pressing pad 41 is supported by a rod 58 carried by bracket 59 which has two leg portions 60 on either side of the frame 1 pivoted as at 61. The leg portions 60 are each formed with a lever portion 62 having a cam surface 63. The levers 55 are provided with a cam engaging portion 64 cooperating with the cam surface 63 of lever portions 62 so that movement of the levers 55 responsive to actuation by lever 36 causes bracket 59 and pad 41 to be moved toward pad 40 to tightly engage the forming member 30 and the garment corner thereon to 50 perform the pressing operation. Spring 65 serves to compensate for various thicknesses of cloth and to properly position the pad 41 during the pressing operation.

55 To summarize the operation of the improved corner forming apparatus of this invention, with the treadle 19 initially in the upper position shown in solid lines in Fig. 2, and the treadle 43 in the mid-position shown in solid lines in Fig. 2 so that forming member 30 is positioned 60 between the heated pressing pads 40 and 41, as shown in Figs. 1 and 3, prong 5 of the garment receiving member is free for the reception of a new unformed garment. After a garment is positioned on the prong 5, the receiving member with

the garment thereon is moved through the opening 3 until the shearing member 13 is contacted. Depression of treadle 19 to the lower position 26 moves shearing member 13 toward the cutting blades 10 to perform the trimming operation, manual pressure being maintained on the prong 5 to keep it in contact with the shearing member 13 during the trimming operation. Release of the treadle 19 to the upper position returns the shearing member 13 to its normal position and release of manual pressure on the prong 5 returns the receiving member with the trimmed garment thereon to its first position. The treadle 43 is then released to upper position 47 swinging supporting arm 32 and forming member 30 to position 39 with the forming member 30 directly above the prong 5. In this position, the trimmed garment may be transferred to the forming member 30 and turned in the transfer operation. Depression of the treadle 43 to its mid-position swings the forming member with the garment thereon between the heated pressing pads 40 and 41. Continued depression of the treadle 43 to the lower position 48 moves the heated pressing pads 40 and 41 together to tightly engage the forming member 30 and the garment corner thereon to perform the pressing operation. Release of the treadle 43 upward to its mid-position releases the pressing pads and continued release of the treadle 43 upward to the upper position 47 causes the forming member 30 to be swung into the position 39 permitting removal of the finished garment.

While the shearing member 13, the forming member 30, and heated pressing pads 40 and 41 may be actuated by a single treadle, the two-treadle operation shown is preferred since it permits release of the heated pressing pads without operation of the cutting mechanism. The heated pressing pads 40 and 41 may be heated by any suitable heating means, such as electric elements in which case a heat controlling device 66 may be mounted on frame 1.

Certain types of garments, such as collars, may be provided with two opposed corners, the corners being the obverse of each other. Thus, in order to perform the trimming, forming, and pressing operations on both corners successively, it is desirable to provide means to reverse the forming means after each operation of the machine so that the opposed corner can be formed and pressed in the next operation. To accomplish this result, the hub 31 of forming member 30 is rotatably mounted in a bearing 67 on arm 32 and is provided with a gear 68. A mating gear segment 69 is pivotally mounted on frame 1 as at 70. A stop 71 limits movement of the gear segment 69 while movement in the other direction is permitted against spring 72. Thus, when arm 32 is moved toward position 39, gear 68 engages gear segment 69 which is prevented from rotating by pin 71, and rotates forming member 30, 180° so that the opposite corner can be operated on in the next cycle. Movement of the arm 32 toward the heated pressing pads 40 and 41, however, causes gear segment 69 to pivot at 70 so that gear 68 is not rotated. In order to permit trimming one corner of the garment while the other is being pressed simultaneously, the distance from the position 39 of the forming member 30 to its second position between the heated pressing pads 40 and 41 should not exceed one half the total length of the garment. This will allow both corners to be operated on

without removing the garment from the machine.

It may also be desirable to inject a small amount of steam-forming liquid onto the heated pressing pads 40 and 41 or onto the garment corner to improve the press. Thus, a steam-forming liquid reservoir container 73 is supported in a supporting member 74 carried by frame 1. A channel 75 communicates with the container 73 and a piston 76 furnishes the liquid to a jet 77 which injects the liquid onto the garment corner between the pressing pads 40 and 41 or onto the pads. Ball check valves 78 and 79 provide the suction and pressure action. The piston 76 is actuated by a lever 80 connected to the legs 60 of bracket 59. Spring 81 returns the piston 76 to its open position. Thus, when lever 55 is engaged to actuate lever portion 62 of legs 60 to move pad 41 to the closed position, lever 80 moves piston 76 inwardly forcing a jet of liquid through ball valve 78 onto the garment, or the heated pads. When the pad 41 is released, spring 81 returns piston 76 to its open position sucking in a new charge of liquid from container 73 through ball valve 79.

It can now be readily seen that this invention provides a compact and simple device for performing trimming, turning, forming, and pressing operations on a multiple thickness cloth garment to form a pointed or rounded corner thereon, all operations being performed by a single operator. Furthermore, this apparatus permits successively forming opposed corners, such as collars, and provides for injecting a small quantity of steam-forming liquid onto the garment or the heated pressing pads during the pressing operation to improve the press and finish secured.

While I have illustrated and described a particular embodiment of this invention, modifications thereof will occur to those skilled in the art. I desire it to be understood, therefore, that this invention is not to be limited to the particular arrangement disclosed, and I intend in the appended claims to cover all modifications which do not depart from the spirit and scope of the invention.

What I claim as new and desire to secure by Letters Patent of the United States, is:

1. Apparatus for performing trimming, turning and shaping operations on a multiple thickness cloth garment comprising a supporting frame, means movably mounted on said frame and adapted in one position to receive said garment thereover with the wrong side out, cutting means on said frame adapted to trim said garment while on said receiving means to remove excess material therefrom, said receiving means being movable into another position to trim said garment on said cutting means, forming means on said frame for receiving said garment thereover with the right side out after said trimming operation, said forming means being arranged adjacent said one position of said receiving means to permit transfer of said garment from said receiving means and reversal of said garment during said transfer, said forming means being shaped to form said garment to the final shape desired, and movable pressing means on said frame normally spaced from said forming means and movable into engagement with said forming means for pressing said garment thereon.
2. Apparatus for performing trimming, turning and shaping operations on a multiple thick-

ness cloth garment to form a corner thereon comprising a supporting frame, means movably mounted on said frame and adapted in one position to receive said garment thereover with the wrong side out, stationary cutting means on said frame adapted to trim said garment while on said receiving means to remove excess material adjacent said corner, said receiving means being movable into another position to trim said garment on said cutting means, forming means movably mounted on said frame adapted in one position to receive said garment thereover with the right side out after said trimming operation, said one position of said forming means being adjacent said one position of said receiving means to permit transferal of said garment from said receiving means and reversal of said garment during said transfer, said forming means being shaped to form said corner of said garment to the final shape desired, said forming means being movable into a second position, and movable pressing means on said frame normally spaced from said forming means in its second position and movable into engagement with said forming means for pressing said corner of said garment thereon.

3. Apparatus for performing trimming, turning and shaping operations on a multiple thickness cloth garment to form a corner thereon comprising a supporting frame, means pivotally mounted on said frame and adapted in one position to receive said garment thereover with the wrong side out, stationary cutting means on said frame adapted to trim said garment while on said receiving means to remove excess material adjacent said corner, movable shearing means pivotally mounted on said frame and adapted to cooperate with said cutting means to trim said garment corner, said receiving means being movable into a second position in contact with said shearing means, said shearing means with said receiving means and said garment corner in contact therewith being movable into shearing relation with said cutting means for trimming said garment corner, forming means pivotally mounted on said frame and adapted in one position to receive said garment thereover with the right side out after said trimming operation, said one position of said receiving means being adjacent said one position of said receiving means to permit transferal of said garment from said receiving means and reversal of said garment during said transfer, said forming means being shaped to form said corner of said garment to the final shape desired, said forming means being movable into a second position, and movable pressing means on said frame normally spaced from said forming means in its second position and movable into engagement with said forming means for pressing said garment corner thereon.

4. Apparatus for performing trimming, turning and shaping operations on a multiple thickness cloth garment to form a corner thereon comprising a supporting frame, means adapted in one position to receive said garment thereover with the wrong side out, said frame having an opening formed therein adapted to pass said receiving means with said garment thereon, stationary cutting blades secured to said frame adjacent said opening and adapted to trim said garment while on said receiving means to remove excess material adjacent said corner, said receiving means being pivotally mounted on said frame whereby said receiving means with said garment thereon can be moved through said frame opening into a second position, resilient means for returning

said receiving means to said one position, said cutting blades being adapted to engage said garment in trimming relation when said receiving means is returned to said one position, forming means pivotally mounted on said frame and adapted in one position to receive said garment thereover with the right side out after said trimming operation, said one position of said forming means being adjacent said one position of said receiving means to permit transferal of said garment from said receiving means and reversal of said garment during said transfer, said forming means being shaped to form said corner of said garment to the final shape desired, means for moving said forming means into a second position, and means for pressing said garment corner on said forming means in said second position thereof.

5. Apparatus for performing trimming, turning and shaping operations on a multiple thickness cloth garment to form a corner thereon comprising a supporting frame, means adapted in one position to receive said garment thereover with the wrong side out, said frame having an opening formed therein adapted to pass said receiving means with said garment thereon, stationary cutting blades secured to said frame adjacent said opening and adapted to trim said garment while on said receiving means to remove excess material adjacent said corner, shearing means pivotally mounted on said frame and adapted to cooperate with said cutting blades to trim said garment corner, said receiving means being pivotally mounted on said frame whereby said receiving means with said garment thereon can be moved through said frame opening into a second position in contact with said shearing means, means for moving said shearing means with said receiving means and said garment corner in contact therewith into shearing relation with said cutting blades for trimming said garment corner, forming means pivotally mounted on said frame and adapted in one position to receive said garment thereover with the right side out after said trimming operation, said one position of said forming means being adjacent said one position of said receiving means to permit transferal of said garment from said receiving means and reversal of said garment during said transfer, said forming means being shaped to form said corner of said garment to the final shape desired, means for moving said forming means into a second position, and means for pressing said garment corner on said forming means in said second position.

6. Apparatus for performing trimming, turning and shaping operations on a multiple thickness cloth garment to form a corner thereon comprising a supporting frame, means adapted in one position to receive said garment thereover with the wrong side out, said frame having an opening formed therein adapted to pass said receiving means with said garment thereon, stationary cutting blades secured to said frame adjacent said opening and adapted to trim said garment while on said receiving means to remove excess material adjacent said corner, shearing means pivotally mounted on said frame and adapted to cooperate with said cutting blades to trim said garment corner, said receiving means being pivotally mounted on said frame whereby said receiving means with said garment thereon can be moved through said frame opening into a second position in contact with said shearing means, means for moving said shearing means with said receiving means and said garment

being shaped to form said corner of said garment to the final shape desired, said forming means being movable into a second position, means movably mounted on said frame for pressing said corner of said garment on said forming means in said second position thereof, means for returning said forming means to said first position, and means for reversing said forming means during each cycle of operation whereby two opposed corners can be formed successively.

11. Apparatus for performing trimming, turning and shaping operations on a multiple thickness cloth garment to form a corner thereon comprising a supporting frame, means adapted in one position to receive said garment thereover with the wrong side out, said frame having an opening formed therein adapted to pass said receiving means with said garment thereon, stationary cutting blades secured to said frame adjacent said opening and adapted to trim said garment while on said receiving means to remove excess material adjacent said corner, shearing means pivotally mounted on said frame and adapted to cooperate with said cutting blades to trim said garment corner, said receiving means being pivotally mounted on said frame whereby said receiving means with said garment thereon can be moved through said frame opening into a second position in contact with said shearing means, means for moving said shearing means with said receiving means and said garment corner in contact therewith into shearing relation with said cutting blades for trimming said garment corner, forming means pivotally mounted on said frame and adapted in one position to receive said garment thereover with the right side out after said trimming operation, said one position of said forming means being adjacent said one position of said receiving means to permit transferal of said garment during said transfer, said forming means being shaped to form said corner of said garment to the final shape desired, a pair of spaced apart heated pressing pads movably mounted on said frame, means for moving said forming means with said garment thereon into a second position between said pressing pads, means for moving said pressing pads together to tightly engage said forming member with said garment thereon for pressing said garment, means for returning said forming means to said one position, and means on said frame cooperating with said forming means for reversing said forming means during each return to said first position whereby two opposed corners can be formed successively.

12. Apparatus for performing trimming, turning and shaping operations on a multiple thickness cloth garment to form a corner thereon comprising a supporting frame, movable means pivotally mounted on said frame and adapted in one position to receive said garment thereover with the wrong side out, stationary cutting means on said frame adapted to trim said garment while on said receiving means to remove excess material adjacent said corner, said receiving means being movable into another position to trim said garment on said cutting means, movable forming means pivotally mounted on said frame and adapted in one position to receive said garment thereover with the right side out after said trimming operation, said one position of said forming means being adjacent said one position of said receiving means to permit transferal of said garment from said receiving means and reversal of said garment during said transfer, said forming means being shaped to form said corner of said garment to the final shape desired, said forming means being movable into a second position, and means movably mounted on said frame for pressing said corner of said garment on said forming means in said second position thereof, the distance between said first and said second positions of said forming means not exceeding one half the length of said garment

of said garment during said transfer, said forming means being shaped to form said corner of said garment to the final shape desired, a pair of movable heated spaced apart pressing pads on said frame, said forming means being movable with said garment thereon into a second position between said pressing pads, said pressing pads being movable together to tightly engage said forming member with said garment thereon for pressing said garment, and means mounted on said frame for injecting a steam-forming liquid between said pressing pads for improving the press provided thereby.

13. Apparatus for performing trimming, turning and shaping operations on a multiple thickness cloth garment to form a corner thereon comprising a supporting frame, movable means pivotally mounted on said frame and adapted in one position to receive said garment thereover with the wrong side out, stationary cutting means on said frame adapted to trim said garment while on said receiving means to remove excess material adjacent said corner, said receiving means being movable into another position to trim said garment on said cutting means, movable forming means pivotally mounted on said frame and adapted in one position to receive said garment thereover with the right side out after said trimming operation, said one position of said forming means being adjacent said one position of said receiving means to permit transferal of said garment from said receiving means and reversal of said garment during said transfer, said forming means being shaped to form said corner of said garment to the final shape desired, a pair of movable heated spaced apart pressing pads on said frame, said forming means being movable with said garment thereon into a second position between said pressing pads, said pressing pads being movable together to tightly engage said forming member with said garment thereon for pressing said garment, reservoir means mounted on said frame for storing a steam-forming liquid, and means operable in response to movement of said pressing pads for injecting a small quantity of said liquid between said pressing pads for improving the press provided thereby.

14. Apparatus for performing trimming, turning and shaping operations on a multiple thickness cloth garment to form corners at two ends thereof comprising a supporting frame, movable means pivotally mounted on said frame and adapted in one position to receive said garment thereover with the wrong side out, stationary cutting means on said frame adapted to trim said garment while on said receiving means to remove excess material adjacent said corner, said receiving means being movable into another position to trim said garment on said cutting means, movable forming means pivotally mounted on said frame and adapted in one position to receive said garment thereover with the right side out after said trimming operation, said one position of said forming means being adjacent said one position of said receiving means to permit transferal of said garment from said receiving means and reversal of said garment during said transfer, said forming means being shaped to form said corner of said garment to the final shape desired, said forming means being movable into a second position, and means movably mounted on said frame for pressing said corner of said garment on said forming means in said second position thereof, the distance between said first and said second positions of said forming means not exceeding one half the length of said garment

corner in contact therewith into shearing relation with said cutting blades for trimming said garment corner, and forming means adapted to receive said garment thereover with the right side out after said trimming operation, said one position of said receiving means being adjacent said forming means to permit transferal of said garment to said forming means and reversal of said garment during said transfer.

7. Apparatus for performing trimming, turning and shaping operations on a multiple thickness cloth garment to form a corner thereon comprising a supporting frame, means pivotally mounted on said frame and adapted in one position to receive said garment thereover with the wrong side out, stationary cutting means adapted to trim said garment while on said receiving means to remove excess material adjacent said corner, said receiving means being movable into another position to trim said garment on said cutting means, forming means pivotally mounted on said frame and adapted in one position to receive said garment thereover with the right side out after said trimming operation, said one position of said forming means being adjacent said one position of said receiving means to permit transferal of said garment from said receiving means and reversal of said garment during said transfer, said forming means being shaped to form said corner of said garment to the final form desired, and a pair of movable spaced apart heated pressing pads on said frame, said forming means being movable into a second position between said pressing pads, said pressing pads being movable together to tightly engage said forming member with said garment thereon for pressing said garment.

8. Apparatus for performing trimming, turning and shaping operations on a multiple thickness cloth garment to form a corner thereon comprising a supporting frame, means adapted in one position to receive said garment thereover with the wrong side out, said frame having an opening formed therein adapted to pass said receiving means with said garment thereon, stationary cutting blades secured to said frame adjacent said opening and adapted to trim said garment while on said receiving means to remove excess material adjacent said corner, shearing means pivotally mounted on said frame and adapted to cooperate with said cutting blades to trim said garment corner, said receiving means being pivotally mounted on said frame whereby said receiving means with said garment thereon can be moved through said frame opening into a second position in contact with said shearing means, means for moving said shearing means with said receiving means and said garment corner in contact therewith into shearing relation with said cutting blades for trimming said garment corner, forming means pivotally mounted on said frame and adapted in one position to receive said garment thereover with the right side out after said trimming operation, said one position of said forming means being adjacent said one position of said receiving means to permit transferal of said garment from said receiving means and reversal of said garment during said transfer, said forming means being shaped to form said corner of said garment to the final shape desired, a pair of spaced apart heated pressing pads movably mounted on said frame, means for moving said forming means with said garment thereon into a second position between said pressing pads,

5 and means for moving said pressing pads together to tightly engage said forming member with said garment thereon for pressing said garment.

9. Apparatus for performing trimming, turning and shaping operations on a multiple thickness cloth garment to form a corner thereon comprising a supporting frame, means adapted in one position to receive said garment thereover with the wrong side out, said frame having an opening formed therein adapted to pass said receiving means with said garment thereon, stationary cutting blades secured to said frame adjacent said opening and adapted to trim said garment while on said receiving means to remove excess material adjacent said corner, shearing means pivotally mounted on said frame and adapted to cooperate with said cutting blades to trim said garment corner, said receiving means being pivotally mounted on said frame whereby said receiving means with said garment thereon can be moved through said frame opening into a second position in contact with said shearing means, resilient means for biasing said receiving means toward said one position, means for operating said shearing means, means operatively connected to said operating means for moving said shearing means with said receiving means and said garment corner in contact therewith into shearing relation with said cutting blades for trimming said garment corner, resilient means for biasing said shearing means away from said shearing position, forming means pivotally mounted on said frame and adapted in one position to receive said garment thereover with the right side out after said trimming operation, said one position of said forming means being adjacent said one position of said receiving means to permit transferal of said garment from said receiving means and reversal of said garment during said transfer, said forming means being shaped to form said corner of said garment to the final shape desired, a pair of spaced apart heated pressing pads movably mounted on said frame, means for operating said forming means, means operatively connected to said last-mentioned operating means for moving said forming means with said garment thereon into a second position between said pressing pads, resilient means for returning said forming means to said first position, said second-mentioned operatively connected means being adapted to move said pressing pads together to tightly engage said forming member with said garment thereon for pressing said garment.

10. Apparatus for performing trimming, turning and shaping operations on a multiple thickness cloth garment to form a corner thereon comprising a supporting frame, means pivotally mounted on said frame and adapted in one position to receive said garment thereover with the wrong side out, stationary cutting means on said frame adapted to trim said garment while on said receiving means to remove excess material adjacent said corner, said receiving means being movable into another position to trim said garment on said cutting means, forming means pivotally mounted on said frame and adapted in one position to receive said garment with the right side out after said trimming operation, said one position of said forming means being adjacent said one position of said receiving means to permit transferal of said garment from said receiving means and reversal of said garment during said transfer, said forming means

whereby trimming and pressing operations can be respectively performed on both of said corners simultaneously without removing said garment from said apparatus.

15. Apparatus for performing trimming, turning and shaping operations on a multiple thickness cloth garment comprising a supporting frame, movable means pivotally mounted on said frame and adapted in one position to receive said garment thereover with the wrong side out, cutting means on said frame adapted to trim said garment while on said receiving means to remove excess material therefrom, said receiving means being movable into another position to trim said garment on said cutting means, forming means on said frame for receiving said garment thereover with the right side out after said trimming operation, said forming means being arranged adjacent said one position of said receiving means

5 to permit transferal of said garment from said receiving means and reversal of said garment during said transfer, said forming means being shaped to form said garment to the final shape.

10 5 desired, means movably mounted on said frame for pressing said garment while on said forming means, and means on said frame for injecting a steam-forming liquid into said pressing means for improving the press provided thereby.

LEO J. TRAHAN.
